H. B. WALTER

BOX AND METHOD OF MAKING THE SAME

Filed Feb. 7, 1923

Inventor
Harrison B. Walter
by Clarence E. McElroy Atty

UNITED STATES PATENT OFFICE.

HARRISON B. WALTER, OF CHICAGO, ILLINOIS, ASSIGNOR TO CHICAGO MILL AND LUMBER COMPANY, OF CHICAGO, ILLINOIS, A CORPORATION OF ILLINOIS.

BOX AND METHOD OF MAKING THE SAME.

Application filed February 7, 1923. Serial No. 617,425.

To all whom it may concern:

Be it known that I, HARRISON B. WALTER, a citizen of the United States, and a resident of Chicago, county of Cook, and State of Illinois, have invented certain new and useful Improvements in Boxes and Methods of Making the Same; and I do hereby declare that the following is a full, clear, and exact description thereof, reference being had to the accompanying drawings, and to the letters of reference marked thereon, which form a part of this specification.

10 This invention relates to improvements in boxes made of fiber or paper board or the like, and consists of the matters hereinafter described and more particularly pointed out in the appended claim.

15 The object of the invention is to produce a collapsible box of the kind known as a "top loading" as distinguished from an "end loading" box, in which the top closure is capable of such attachment to the body, when closing and sealing the box that this attachment may be accomplished not only 20 quickly, so as to result in rapid handling of the box after it is packed, but also by means of the sewing process described in Letters Patent No. 1,449,467 issued to me on the 27th day of March, 1923. The box is of 25 special advantage to those doing a large volume of business requiring rapid packing and handling, in that the sealing may be carried on upon a plurality of boxes in succession,—the boxes being advanced to the sewing position on a continuous moving belt or other 30 conveyor.

35 The improved box requires a minimum of stock and may be made at low cost of material and labor. Its several advantages will 40 appear more fully as I proceed with my specification.

In the drawings:—

Fig. 1 is a perspective view of the improved box.

45 Fig. 2 is a view representing a partial section through the box in a plane indicated by the line 2—2 of Fig. 1.

Fig. 3 is a plan view of a blank for making the body of the box.

50 Fig. 4 is a plan view of the blank for the ends of the box.

Referring now to that embodiment of the invention illustrated in the drawings:—10, 10 indicate the sides of the box; 11, the

bottom of the box; 12, 12, the ends of the 55 box; and 13 indicates the top closure.

The body of the box is made, as shown, from an elongated blank (see Fig. 3) of approximately a width equal to the intended 60 length of the box. This blank is cut and creased to provide the part 11 for the bottom of the box, two parts 10, 10 at each side thereof for the sides of the box, a part 13 at one end of the blank for the top closure of the box, and, preferably a short flap extension 13^a at the other end of the blank.

The blank is creased transversely on parallel lines 14 to define the several parts mentioned. The blank is also creased longitudinally on parallel spaced lines 15 which define the length of the box body-forming parts, except the top closure part 13,—said lines 15 terminating at the points where they meet the crease lines 14, which define the fold line of the top closure part 13. The 70 blank has lateral extension parts 10^a and 11^a, which provide short, folding end extensions of the two side parts and of the bottom part respectively. The top closure part is made longer than the distance between the longitudinal, crease lines 15, 15 by extensions 13^b, 13^b which are preferably 75 made of the same width as the other lateral extensions of the blank. The flap extension 13^a at the other end of the blank is cut 80 somewhat shorter than the distance between the longitudinal crease lines 15, 15.

The ends of the box each consists of a blank of an area equal to the cross sectional area of the box, and of a top flap extension 90 12^a defined by a crease line 12^b. The flap extensions 12^a of the end parts 12, as well as the extensions 13^b of the top closure part 13, are bevelled at their ends as indicated respectively at 12^c and 13^c.

To form the box, the body blank (shown in Fig. 3) is bent into box form with the bottom 11 horizontal and the sides 10, 10 in vertical relation thereto. An end blank 12 is then brought into the required relation, with its edges coinciding with a crease mark 15 at one side of the body blank. The extensions 11^a and 10^a respectively, of the bottom and side forming parts of the blank are folded against the end blank (as shown— 100 against the outer face of said end blank). The side extensions are then attached to the said end blank by means of the "fiber lock" 105

made by the process described in an application heretofore filed by me on the 3rd day of February, 1923, Serial Number 616,664, in which the overlapped parts are joined by means of cement with points or detents of one part depressed into the body of the other part. The other end blank is treated and applied in the same manner. This puts the box in condition for loading, with the 10 flange extension 12^a on the ends 12 in vertical position (being ready to be folded down into a horizontal position) and with the top closure part 13 and the short flap extension 13^a (when the same is used) laid back to 15 open up the box.

The box is then loaded. After loading, the flap 13^a and the flap extensions 12^a, 12^b of the ends of the box are turned down and the top closure 13 is folded down against 20 said several flaps to close the box, the same extending entirely across the open top of the box and providing a complete closure therefor. As fast as the boxes are loaded they 25 may be placed on a suitable conveyor and advanced in succession to sewing machines or other devices adapted to sew by means of a continuous thread or cord the extensions 13^b, 13^a of the top closure 13 to the flap extensions 12^a, 12^b of the ends. This seals the 30 box at the ends. As the top closure 13 extends completely across the box and as there are no laps or folds in the top closure intermediate the sides of the box, no obstruction 35 or impediment is presented to the operation of the sewing machines, which are thus enabled to apply the sewed joint with smoothness and continuity, proceeding from one box to the next in succession as the boxes are brought into sewing position by the conveyor. The improved box is thus of great 40 advantage where the top closure is to be attached and sealed in this manner.

Generally, and preferably, a sealing strip 45 16 is applied at the free edge of the top closure 13 to seal said closure along said edge to the proximate side 10. The flap 13^a pro-

vides a supplemental support for the top closure along said edge and a strengthening brace for the corners of the box at said edge.

The folding extensions 12^a which provide 50 the seats for the top closure and the end extensions 13^b of said top closure, provide, after they are attached together, projecting end "hand holds" or "grips" at the top of the box, which are convenient in lifting and 55 handling the box. By reason of the inclined parts 12^c and 13^c at the ends of the respective extensions 12^a and 13^b, projecting corners are eliminated.

While in describing my invention I have 60 referred to several details of construction and mechanical arrangement, it is to be understood that the invention is not thereby in any way limited except as may be pointed out in the appended claim.

I claim as my invention:—

A box made of blanks of fiber, paper board or the like, comprising a blank cut and creased to provide a bottom, sides and a single top closure flap, the sides and bottom having foldable end extensions and the top closure flap having non-folding end extensions, and blanks cut to form the ends of the box and having top foldable extension flaps; said first named blank being folded 70 to form the main body of the box and having the end extensions of its sides and bottom folded against and secured to the sides and bottom parts of said end blanks by means of a joint which includes cement and the distortion of parts of the extensions into the body of the blanks forming the ends, and the extensions at the top of said end blanks being adapted to be folded down to extend 75 outwardly from the box to form seats in the plane of the top of the box to receive and to be attached to the extensions of the single top closure of the box.

In testimony that I claim the foregoing as my invention, I affix my signature this 31st day of January, A. D. 1923.

HARRISON B. WALTER.
